UNITED STATES PATENT OFFICE.

JOHN T. FANNING, OF CHICAGO, ILLINOIS.

DESIGN FOR A SPROCKET-WHEEL.

SPECIFICATION forming part of Design No. 29,948, dated January 3, 1899.

Application filed September 10, 1898. Serial No. 690,696. Term of patent 3½ years.

To all whom it may concern:

Be it known that I, JOHN T. FANNING, residing at Chicago, in the county of Cook and State of Illinois, have invented and produced 5 a new and original Design for Sprocket-Wheels, of which the following is a specification, reference being had to the accompanying drawings, forming a part thereof.

In the drawings, Figure 1 shows my new design in side elevation. Fig. 2 is a central vertical section of the same.

The leading or characteristic features of the design consist in the wheel having the shape or configuration shown in the drawings, in 15 which *a* denotes the hub. *B* is the shaft-opening. *c c* are spokes. *d d* are ornamental tips extending inwardly from the rim. *e e* are openings between spokes *c*. *f* is the rim. *g g* are sprocket-teeth extending outwardly from rim *f*. *h h* are holes in the spokes and are adjacent rim *f*. *i i* are holes in spokes

c and are located adjacent hub *a*. *k* are small circular holes in the spokes and are located between holes *h* and *i*. Holes *h*, *k*, and *i* are of the contour shown in the drawings. 25

The spokes *c* are wide near the hub, narrow at their mid-length, and broadened near the rim *f* to unite with tips *d*, as shown. The reversely - curved edges of the spokes are joined near hub *a* and are extended to join 30 tips *d*. By such arrangement or collocation of the spoke edges openings *e* of the familiar "heartshape" are formed between the spokes.

Having thus described my invention, what I claim as new, and desire to secure by Letters 35 Patent, is—

The design for a sprocket-wheel, substantially as herein shown and described.

JNO. T. FANNING.
